UNITED STATES PATENT OFFICE.

STANLEY A. KOZIELSKI, OF CLEVELAND, AND FRANCIS J. BOOTH, OF SOUTH EUCLID,
OHIO.

CASE STRUCTURE.

Application filed October 8, 1924. Serial No. 742,431.

To all whom it may concern:

Be it known that we, STANLEY A. KOZIELSKI, of Cleveland, and FRANCIS J. BOOTH, of South Euclid, both in county of Cuyahoga and State of Ohio, both citizens of the United States, have jointly invented a new and useful Improvement in Case Structures, of which the following is a specification.

Our invention relates to the structure of cases.

One of the objects of our invention is a simple, inexpensive, and neat case.

Another object is to provide such a case with independent walls and top and bottom and to hold these members together by one mechanism in each corner so that the case can readily be assembled or taken apart and packed into compact form for shipment or storage.

Another object is to provide such a case with finishing strips to avoid abutting the members on each other edgewise and to support these members and to provide a neat appearance of the joints along the edges of two adjoining members.

Another object is to provide such a case with a frame, metallic or otherwise, forming a unitary structure when the case is assembled and adapted to hold or retain the walls and the top and bottom in relation to each other without clamping or otherwise rigidly confining the edges of these members except across the thickness thereof to prevent breaking or warping of the plates due to changes in temperature or other causes.

In the accompanying drawing we have illustrated our invention as applied to a show case having a metallic frame and wall and top and bottom of glass without any door or other opening as frequently constructed for use in radio outfits.

In this accompanying drawing,

Fig. 1 is a side view of a show case embodying the features of our invention.

Fig. 2 is an end view of Fig. 1.

Fig. 3 is a plan view of one corner of Fig. 1.

Fig. 4 is a typical section of the corners of the case, indicated by the line 4-4 in Fig. 3, showing the relations between the

screw and the plates and between the corner plate and the corner cap and the finishing strips retained thereby.

Fig. 5 is a perspective view of the end of a finishing strip showing the notch therein.

Fig. 6 is an end view of the corner cap showing the projections on the three inner faces of the walls thereof.

Fig. 7 is a sectional view of a portion of one corner of the case showing one of the projections on the corner cap engaging one end of a finishing strip.

Fig. 8 is a perspective view, on a larger scale, of a corner plate.

Fig. 9 is a sectional view of one corner of the case without finishing strips, showing the corners of the glass cut away to clear the screw.

Fig. 10 is a typical section of two adjoining plates, as indicated by the line 10-10 in Fig. 1 for instance, showing the relations of the finishing strips to the plates and of the plates to each other endwise.

Similar reference characters refer to similar parts throughout the views.

The case shown in the drawing comprises principally, a frame and four walls and a top and a bottom.

The frame is formed of the outside finishing strips 10, the inside finishing strips 11, and the corner pieces A.

All of the finishing strips are made of the same size of stock in the present instance, thereby reducing the cost of production.

The corner pieces A are all made with the same corner holding means and of the same general contour except that the corner pieces on the bottom have feet although these feet may be omitted if desired.

Each of the corner pieces A comprises the corner plate 12 and the corner cap 13 held in position to each other by the screw 14 and the nut 15 threaded thereon.

The corner plate 12, shown in Fig. 8, has a triangular base and is of conical formation. The hole 16 is in alignment with the axis of the cone and permits the screw 14 to pass through. Each of the corners 17 of this cone has the recess 18 of a depth slightly less than the thickness of the material of

the finishing strips 11 thereby preventing the conical faces 19 from abutting the glass and permitting the strips 11 to freely abut the glass when the case is assembled as illustrated in Fig. 4 for instance.

The corner cap 13, shown in Fig. 6, has the three flanges 20 joined to each other to form the triangular and conical depression 21 with the inner faces of these flanges of 10 the same angles as the faces 19 of the corner plates 12. Each corner of this depression 21 has the inwardly extending projection 22 to engage the strips 10 as will appear presently. Each of the corner caps 13 has the 15 boss 23 projecting outside of the flanges 20 and disposed in alignment with the axis of the conical depression 21 and has the opening 24 for the screw 14 also in alignment with the axis of the depression 21.

20 The arrangement or disposition of the screw 14 is somewhat difficult to show on a flat drawing but it is believed readily understandable when it is remembered that each screw passes through one of the corners of 25 the case at an angle of forty five degrees with each of three adjoining plates as more definitely illustrated in Fig. 9.

Each of the finishing strips 10 is of angle iron formation cross-sectionally and each 30 end of each strip has the notch 25 adapted to engage the projections 22 when the case is assembled.

Each of the finishing strips 11 is of angle iron formation cross-sectionally similar to 35 the strips 10 but have no notches in the present instance.

The strips 11 may also be provided with notches similar to the notches 25 in the strips 10 in which case projections, similar to the 40 projections 22, are provided on the recessed portions of the faces 19. Neither of the strips may have any notches and neither of the corner pieces may have projections; in such cases the friction between the ends of 45 the finishing strips and the corner pieces is relied upon to hold the frame together. It is preferred however that some sort of engaging means is employed to definitely locate the several members in desired relation 50 to each other.

When assembling the case shown, any of 55 the three adjoining plates of the case are held in approximately the desired position in relation to each other; the finishing strips 10 are then placed over the outside of the edges of each two adjoining plates and the finishing strips 11 are then placed on the inside of the edges of each two of the adjoining plates as seen sectionally in Fig. 10; the corner plate 12 is then placed in the corner formed by these three adjoining plates; the corner cap 13 is then placed over the corner formed by these adjoining plates; and the screw 14 is then inserted through 60 the corner plate and the corner cap and

tightened up; thereby forcing the corner plate and the corner cap toward each other and combining the adjoining plates and strips of each corner into a unitary joint which can easily be assembled or taken apart.

Each of the remaining corners of the case may be assembled similar to the corner described.

The notches 25 and the projections 22 75 serve the purpose of definitely locating the corner pieces in relation to the finishing strips, thereby forming a unitary frame structure with independent wall and top and bottom plates held therein by the sides of 80 the edges thereof only and not confined edgewise so that the adjoining plates do not abut each other and permit these plates to expand or contract under temperature change or otherwise to prevent the breaking 85 or warping thereof.

We are aware that modifications other than those shown and described and pointed out may be made; therefore, without limiting ourselves to the precise construction and arrangement of elements shown and described and pointed out,

We claim:—

1. A case comprising, individual wall and top and bottom plates, a frame composed of 95 parallelly disposed pairs of inner and outer finishing strips of L-shaped cross-section, each of the outer finishing strips having a notch near each end thereof, a corner plate 100 on the inside of each adjoining corner of said finishing strips and having rabbeted out outer faces engaging three adjoining ends of said inside finishing strips, a corner cap on the outside of each of said corners opposite 105 said corner plates, each of the said caps having an inwardly extending projection on each of the three faces thereof to engage said notches, and a bolt passing through each of 110 said oppositely disposed plates and caps for drawing said plates and caps toward each other and thereby dispose said projections in said notches and hold said strips in relation to each other to complete said frame and clamp the first mentioned plates between said strips.

2. A case comprising, individual wall and top and bottom plates having the edges thereof spaced from each other, finishing strips of L-shaped cross-section on the inside 120 of each two adjoining edges of said plates, finishing strips of L-shaped cross-section on the outside of each two adjoining edges of said plates and each end thereof having a notch, a corner plate on the inside of each adjoining corner of said case and having rabbeted out outer faces engaging three adjoining ends of said finishing strips on the 125 inside of said plates, a corner cap on the outside of each of said corners, the said caps having an inwardly extending projection on 130

each of the three faces thereof to engage said notches, each of said caps also having a cylindrical extension, and a bolt passing through each of said oppositely disposed

5 caps and plates with the head thereof flush with the outer end of said extension for drawing said caps and plates toward each

other and thereby dispose said projections in said notches and hold said strips in relation to each other and clamp the first mentioned plates between said strips. 10
